TOOL FOR ASSEMBLING PIPES

Marion W. Pearson, Tuscaloosa, Ala., assignor to Central Foundry Company, New York, N.Y., a corporation of Maine

Filed Aug. 12, 1965, Ser. No. 86,559

Term of patent 14 years

(Cl. D54—13)

FIG. 1

FIG. 2

FIG. 3

FIG. 5

FIG. 4

FIG. 6

FIG. 1 is a perspective view;
 FIG. 2 is a side elevation view;
 FIG. 3 is a side elevation view opposite to FIG. 2;
 FIG. 4 is an end elevation view;
 FIG. 5 is an end elevation view opposite to FIG. 4; and
 FIG. 6 is a plan view.

The handle is broken away in part in FIGS. 2, 3, 4 and 5 for convenience of illustration.

I claim:

The ornamental design for a tool for assembling pipes, substantially as shown and described.
